SHOE HOLDER

John Clayton Hollister, Sr., 4683 San Sebastian Ave.,
Oakland, Calif.

Filed Apr. 7, 1958, Ser. No. 726,936

9 Claims. (Cl. 15—267)

This invention generally relates to devices for supporting and releasably clamping articles, and is more particularly directed towards such a mechanism specifically utilized for shoes.

As is well known, it is extremely difficult for a person to shine his own shoes. If the shoes are on the person's feet, it is practically impossible to apply the proper brushing or buffing required. Conversely, it is just about as difficult to hold a shoe in one hand and attempt to perform an adequate shining job on the shoe with the other hand. Accordingly, most persons either neglect proper shoe grooming or are required to pay others to perform this task. While various home shoe polishing kits have been marketed, none of such units have overcome the initial problem of supporting the shoe in a convenient manner so that the shining operation might be performed.

It is accordingly an object of the present invention to provide a device adapted to support a shoe during polishing or like operations in which the shoe is engaged entirely on the sole thereof, leaving an unobstructed area over and adjacent the sides of the shoe for movement of a brush, cloth or the like.

Another object of the invention is to provide a device of the type described in which the shoe is securely though releasably clamped in a fixed position, thereby leaving both hands of the user free for performing the shoe shining operation, and which may be readily adjusted to accommodate a wide range of shoe lengths and widths.

A further object of this invention is to provide a shoe holder as above defined which may be readily inserted in and removed from a vertical wall support so as to avoid projection of the device into the room when not being used.

Yet another object of my invention is to provide a shoe holder which may be economically produced and which is constructed in such a manner as to give substantially indefinite use without servicing or other maintenance difficulties.

A further object of the invention is to provide a shoe holder of the character described in which the shoe sole may be easily clamped at two selected positions along the length thereof with one of the clamping members being positioned at a higher elevation than the other clamping member so as to insure proper shoe retention without deforming the normal arch portion of the shoe.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

2

Figure 1 is a perspective view of the shoe holder of the present invention.

Figure 2 is a top plan view.

Figure 3 is a side elevational view.

5 Figure 4 is a cross-sectional view through one of the clamping members on an enlarged scale and taken substantially at line 4—4 of Figure 3.

Figure 5 is a similar cross-sectional view taken at line 5—5 of Figure 3 and illustrating the other clamping member.

10 Figure 6 is a cross-sectional view taken at line 6—6 of Figure 4.

Figure 7 is a perspective view similar to Figure 1, but illustrating a modified form of shoe holder.

Figure 8 is a cross-sectional view similar to Figure 4, but illustrating a modified form of clamping mechanism.

15 As illustrated in Figures 1 through 6 of the drawings, the shoe holder of the present invention generally includes a base portion 12 adapted to support a shoe 13, a fixed clamping member 14, a movable clamping member 16, and means 17 permitting ready installation or detachment of the device from a vertical wall 18 or the like. Broadly speaking, the sole 19 of shoe 13 is adapted to be seated on portion 12 whereby clamping mechanism 14 may engage opposite edge portions of the sole. The heel 21 is likewise seated on a longitudinally spaced portion of the base 12 with the normally elevated sole portion 22 in the area of the arch of the shoe being engaged 20 and secured by the other clamping mechanism 16. It will also be later made clear that at least one of the clamping members is adapted for longitudinal movement along the base so as to provide for shoe sole engagement at selected positions, and both clamping members are 25 adapted to accommodate a wide range of shoe widths.

30 For reasons of economy of production and simplicity and strength of design, base portion 12 is preferably formed of a pair of complementary metal stampings. However, it will be appreciated that other forms of 35 constructional techniques could be used, such as molding from a suitable plastic material, cutting angle iron to shape, etc. Each of the respective sections includes what might be termed a vertical flange 26 and a horizontal flange 27, and in practice, the vertical flanges 26 are 40 secured together in any suitable manner whereby the horizontal flanges 27 provide a substantially continuous base surface for supporting of the shoe 13. The flanges 26 increase in height from the rear end 30 thereof, and adjacent their front ends are deformed to provide tabs 28 disposed at right angles to the general planes of each 45 of the flanges 26 and 27. The tabs are utilized in providing a releasable attachment of the device with the support 17. In this latter regard, it will be noted that means 17 includes a bracket having a wall 31 adapted to 50 be secured to the wall 18 by screws 32 or the like with the vertical edge portions of wall 31 deformed to define opposed inwardly extending channels 33 having a maximum spacing therebetween at the upper ends thereof and a lesser spacing at their lower ends. The tabs 28 have a like taper whereby they may be readily placed 55 into the channels from the upper ends thereof and slid downwardly until firmly wedged in operative position as illustrated in the drawings. This, of course, permits ready removal of the device from the bracket means 17 when not in use, but when operatively installed, the bracket provides a rigid support for the device and the shoe clamped thereto.

60 The horizontal flanges 27 terminate in spaced relation to the tabs 28 and may extend to the rear end 30 of flanges 26. As seen in Figures 1 and 2 of the drawings, each flange 27 has a relatively narrow width for the greater portion of the length thereof with the forward

portion thereof having a wider width so as to better accommodate the generally greater width of the forward sole portion 19 of the shoe 13.

The forward clamping mechanism 14 is positioned substantially centrally of the wider portion of the flange 27, and, as previously explained, is adapted to releasably engage and clamp the sole 19 of the shoe from entirely subjacent the shoe so that the entire upper and side portions of the shoe itself are unobstructed and easily accessible for brushing, polishing and the like. As best illustrated in Figures 2, 3, 4 and 6 of the drawings, clamping mechanism includes a pair of cooperating elements movable laterally of the longitudinal axis of the device for selectively locking and releasing a shoe sole therebetween. In greater detail, each of the horizontal flanges 27 is provided with a stud or rivet 36 having the upper head countersunk in the flange, a stem depending therefrom and a lower head. The stem is slidable relative to a slot 38 of a metal strip 39, the latter being maintained immediately subjacent the lower surface of flange 27 by virtue of the lower head of rivet 36. Since the rivet is secured to the flange, the strip 39 is movable laterally of the flange and the outer end of the strip is provided with an upturned lug 41 having an inwardly extending projection 42. Since the projections 42 on the sides of the respective flanges 27 face each other, it will be appreciated that if the strips are caused to move towards each other, the lugs 41 may be caused to engage opposed portions of the shoe sole 19 with the projections insuring against vertical displacement of the shoe from the base portion 12.

To provide for selective lateral movement of the strips on such base portion, the vertical flanges 26 are apertured as indicated at 44 to receive a stud element 46, the latter having a central portion 47 of reduced diametrical size and end portions 48 and 49 having contrary running threads provided thereon. The respective portions 48 and 49 are threadedly engageable with threaded openings provided in depending ears 51 extending from the inner end of each strip 39. One of the threaded portions is provided with a shank extension 52 by means of which the stud 46 may be rotated to effect opening and closing of the opposed lugs 41. It will be noted that the opening 44 in the vertical flanges 26 is sufficient to freely pass the threaded portions 48 and 49 such as in initially assembling the unit.

Referring now to the rearward clamping mechanism 16, in addition to its shoe sole engaging function, it has two distinguishing characteristics over the clamp 14 just described. First, it is capable of longitudinal movement along the base 12, and secondly, it is positioned substantially above the level of clamp 14 so that it may engage the raised arch sole portion 22 of the shoe immediately forward of the shoe heel 21.

The foregoing is preferably accomplished in the following manner. As to elevating the clamp, there is provided a horizontal wall 56 disposed in spaced parallel relation to flanges 27 by means of vertical walls 57 being suitably slotted at 58 and 59 to receive flanges 26 and 27. Such slots likewise permit the walls to slide along the base portion 12 from and towards clamping mechanism 14. Between the vertical walls 57 and above flanges 27 are strips 61 corresponding to strips 39, and likewise have slots 62 along their lengths, upturned lugs 63 and inward projections 64 at their outer ends, and depending threaded ears 66 at their inner ends, the latter receiving a double reversed threaded stud element 67. The central portion of wall 56 is provided with an apertured depending member 68 through which stud 67 may extend. In this manner, it will be evident that the lugs 63 and projections 64 are capable of clamping the arch sole portion of the shoe in the same manner as the lugs 41 engaging the forward sole portion.

From the above description, the operation of the device will be made clear. The user is only required to open

the respective clamp mechanisms 14 and 16 sufficient so that the shoe 13 may be placed on the base 12, formed of the complementary flanges 27, with the toe of the shoe facing the bracket 17. The clamps may thus be easily tightened either manually or with a socket type key and the shoe will then be firmly anchored to the base in position for shining, polishing, etc., with the entire shoe accessible and unobstructed. Upon completion of the polishing, the clamps are released and the shoe easily removed.

Figure 7 illustrates a slightly modified form of shoe holder. In this embodiment, both ends of the device are capable of insertion into the wall bracket 17 so that either the toe or heel of the shoe faces the user for more convenient shining. This is accomplished by providing tabs 28 at each end of the flanges 26. While brackets are shown on each end of the device, it will be appreciated that this is only for purpose of illustration, since in practice only a single bracket would be secured to a wall surface, and the ears 28 at one end or the other of the device would be inserted therein. It will also be noted that flanges 27 terminate in spaced relation to the rear end ears 28 so as to permit assembly of the raised clamp mechanism 16 onto the base, notwithstanding the provision of the rear ears. Thus, even though the rear ears prevent the mechanism 16 from being installed from the rear end of the unit, the spacing between such ears and the commencement of flanges 27 is such to permit the vertical slots 58 in the walls 57 (such parts corresponding to similarly designated parts shown in Figure 5) to be seated over the flanges 26, and the mechanism may then be slid forwardly until the slots 59 engage the flanges 27.

In Figure 8, in place of the threaded mechanism for moving the clamp lugs selectively from and towards each other, I have provided a simpler resilient engagement of the clamp lugs with the shoe sole. While the forward clamp is illustrated, the same construction could be utilized on the rear clamp as well. As illustrated, clamp strips 71 are slotted at 72 to receive a depending rivet 73, and the strip ends have upstanding sole engaging lugs 74 with inward projections 76 at their upper ends. However, the lugs also have a downwardly extending ear 77 depending below the plane of the strips to which are secured the respective ends of a tension spring 78. This spring normally causes the lugs to approach each other and assume their closest position. In operation, the user can force the lugs apart by sliding the shoe sole therebetween, and the action of the spring will cause the lugs to snugly engage the sole. While this type of clamp does not have the positive locking action of the type previously described, it is obviously advantageous from a time and convenience standpoint.

What is claimed is:

1. A shoe holder comprising a longitudinally extending base having a planar horizontal portion adapted to support the sole of a shoe, a first clamp member having a pair of opposed shoe sole engaging elements extending upwardly from opposite sides of said portion, a second clamp member longitudinally spaced from said first clamp member and having a pair of opposed shoe sole engaging elements extending upwardly from opposite sides of said base portion, means for selectively moving the respective sole engaging elements of each pair transversely of said base portion together for clamping a shoe sole therebetween and apart for releasing such sole, and one of said clamp members being slidable along the length of said base portion whereby the longitudinal spacing between said clamp members may be selectively varied.

2. A device as set forth in claim 1 in which said slidable clamp member is provided with a horizontally disposed wall adapted to support a portion of a shoe sole positioned above the general plane of said planar horizontal portion.

3. A device of the character described comprising a base having a horizontally disposed and longitudinally extending surface adapted to support the sole of a shoe, a first clamp mechanism positioned subjacent said surface

and transversely thereof and including a pair of lugs extending upwardly above said surface on opposite sides thereof, means providing selective transverse movement of said lugs from and towards each other in unison, a second clamp mechanism including a bracket movable along said base and having a wall disposed above said base surface, in substantial parallel relationship thereto, a pair of aligned elements supported on said bracket intermediate said wall and said base for transverse unitary movement relative to said base, and a pair of lugs extending upwardly above said wall carried on the ends of the respective elements, the lugs in each pair being disposed generally equidistant from the longitudinal center of said base.

4. Apparatus as set forth in claim 3 in which at least the lugs in one of the pairs thereof are operatively connected by a spring whereby said lugs are resiliently urged towards each other.

5. Apparatus as set forth in claim 3 in which at least the lugs in one of the pairs thereof are operatively carried by a pair of aligned strip elements, a stud having oppositely directed thread portions selectively engageable with the respective strip elements whereby stud rotation results in movement of said lugs selectively towards and away from each other.

6. A shoe holder comprising a longitudinally extending base having a relatively narrow horizontally disposed upper surface and a vertical flange depending from substantially centrally thereof, said flange extending beyond one end of said surface and having means thereon adapted for releasable mounting to a wall bracket, a first clamp mechanism including a pair of aligned elements positioned subjacent said surface on opposite sides of said flange and slidably supported on said surface for movement transversely of said base, a second clamp mechanism opera-

tively mounted on said base and including a pair of aligned elements mounted for transverse movement relative to said base, each of said elements having an upstanding lug extending above said surface, and means for moving each pair of said elements and the lugs carried thereby selectively from and towards each other.

7. Apparatus as set forth in claim 6 in which said mounting means includes a deformed portion of generally T-shaped form in which said flange provides the central leg thereof.

8. Apparatus as set forth in claim 6 in which said second clamp mechanism includes a bracket having a top wall and opposed side walls, said side walls having a pair of intersecting slots therein slidably receiving the flange and upper surface of said base, said top wall being spaced above said surface, and said aligned elements being positioned between said top wall and said surface and being supported from said top wall for said transverse movement.

9. Apparatus as set forth in claim 8 in which said flange at the end thereof adjacent said second clamp mechanism continues longitudinally beyond said surface a distance at least equal to the spacing between said side walls and terminates in a deformed bracket engaging portion.
